UNITED STATES PATENT OFFICE.

EMIL NOPPEL, OF PHILADELPHIA, PENNSYLVANIA.

OVERFLOW-STOP FOR LIFT AND FORCE PUMPS.

No. 927,003.

Specification of Letters Patent.

Patented July 6, 1909.

Application filed November 10, 1908. Serial No. 461,896.

To all whom it may concern:

Be it known that I, EMIL NOPPEL, a citizen of the United States, residing in the city and county of Philadelphia, State of Pennsylvania, have invented a new and useful Overflow-Stop for Lift and Force Pumps, of which the following is a specification.

My invention relates to a new and useful overflow stop for lift and force pumps and 10 consists in providing means for preventing the air from reaching the overflow in a sink, basin, etc., and of means for positively locking the stop in position.

It further consists in providing means for 15 engagement with a hose coupling.

It further consists of other novel features of construction, all as will be hereinafter fully set forth.

Figure 1 represents a perspective view of 20 an overflow stop and a drain outlet in detached position showing the parts in proper relation to each other. Fig. 2 represents a sectional view thereof. Figs. 3 and 4 represent sectional views showing different forms 25 of expanders which may be employed. Fig. 5 represents a side elevation of a portion of a hose showing a coupling attached thereto.

Similar numerals of reference indicate corresponding parts in the figures.

30 Referring to the drawings, I have found in practice in the use of a lift and force pump that it is necessary to prevent the air from the pump from reaching the overflow outlet of the sink, basin etc., and that it is further 35 necessary to lock the stop in position in the drain and in the drawings, I have shown a construction for these purposes and which I have found, operates successfully, in practice, but it is to be understood that other instruments may be employed, changes 40 may be made in the construction and the arrangement of the parts may be varied and I do not, therefore, desire to be limited, in every instance, to the exact construction as 45 herein shown and described but desire to make such changes as may be necessary.

1 designates one form of a drain outlet used in sinks, basins, etc., which is provided with 50 openings 2 in the sides thereof which lead to the overflow of the sink, basin, etc., and which outlet is provided with suitable bars or stops 3 or other suitable means for preventing solid objects from entering the drain.

4 designates the body of the overflow stop 55 which is preferably formed of rubber or other suitable resilient material and which

has a depending portion 5 forming part of the body adapted to be seated in the drain outlet and which is provided with a suitable bore.

6 designates a tube or sleeve having the flaring end 7 which is preferably bell-shaped and the outer wall of which is provided with the screw threads 8, said tube 6 forming a stiffener and expander, as will be hereinafter described, and is adapted to be seated in the bore of the body 4 and the depending portion 5, it being understood that the tube may be of any suitable size and thickness and the bore thereof may be of any diameter.

9 designates a nut which in the present instance is adapted to be seated in a recess in the upper portion of the body 4 and which nut is adapted to engage with the threads 8 on the expander 6. I preferably place a 75 washer between the nut 9 and the shoulder formed in the body portion 4 and said nut in the present instance being provided with a flange 12 between which and the upper edge of the body 4, I place a washer 13. If desired, the upper edges of the nut may be milled or provided with suitable nicks as at 14 for ease of manipulation.

The operation of the device just described will be readily apparent. When it is desired 85 to place the stop in position in the drain outlet the flaring end 7 of the expander 6 is lowered in the bore by suitable rotation of the nut 9 and the depending portion 5 of the body is inserted in the drain outlet a suitable 90 distance in order to effectually close the outlet opening 2 therein. By now properly rotating the nut 9 the expander 6 is moved up in the bore causing the flaring end 7 to expand the bore and force out the lower portion 95 of the depending portion 5 against the walls of the drain outlet, tightly locking the stop in position so that when the lifting force pump is in use the operator need pay no attention to the stop as it will be firmly locked 100 or held and thus the pump can be effectually operated without displacement of the stop. In order to release the stop, the nut 9 is rotated in the opposite direction lowering the expander 6 and with it the flaring end 7 so 105 that the wedging action ceases and the stop can be removed.

While I have shown the nut 6 as seated in the recess 10 it will be understood that any suitable form of nut may be employed and the engagement with the body may be in any desired manner it only being necessary to

provide a construction in which the rotation of the nut which is engaging with the expander 6, will cause the same to be moved up and down in order to provide for proper 5 expansion or contraction of the depending portion 5. It will be noted that the nut on the expander 6 projects a suitable distance above the top of the nut 9 and by this means

I am enabled to connect a coupling 15 with 10 the end of said expander 6, which coupling is in suitable connection with a hose 16, so that the stop is adapted for use with the hose as well as a lift and force pump.

In the construction shown in Fig. 3, I have 15 shown an expander 6 the same as shown in Fig. 2 excepting that I have provided the recesses or cut away portions 17 to accommodate one of the cross bars 3 in order that the expander will be suitably seated in the drain 20 outlet 1 so that the depending portion 5 will close the outlet openings 2. In some instances I may provide the expander 6 with the oppositely turned jaws 18 and 19 on opposite sides of the expander which are 25 adapted to be placed in engagement with one of the cross bars 3 in order to assist in the locking action of the expander.

Having thus described my invention, what I claim as new and desire to secure by Letters Patent, is:—

1. In a device of the character described, a hollow body formed of resilient material and adapted to be inserted in a drain outlet, means carried by said body for preventing 35 collapse thereof and adapted to be suitably actuated for expanding the body for locking the same in said drain outlet.

2. In an overflow stop for lift and force pumps, a resilient body having a recess in its 40 upper portion and having a depending portion adapted to be inserted in a drain inlet, means for expanding said depending portion for locking the same in said outlet and a means seated in said recess and engaging said 45 expanding means for actuating the same.

3. In an overflow stop for lift and force pumps, a resilient body adapted to be inserted in a drain outlet and a stiffening sleeve 50 suitably carried by said body having a flaring end adapted to be actuated to expand said body for locking the stop in the drain outlet.

4. In an overflow stop for lift and force

pumps, a resilient body adapted to be inserted in a drain outlet and having a bore 55 therethrough, a stiffening sleeve seated in said bore and having a flaring end, and means producing relative movement between the sleeve and resilient body whereby the flaring end expands the body for locking 60 the same in the drain outlet.

5. In an overflow stop for lift and force pumps, a resilient body adapted to be inserted in a drain outlet and having a bore 65 therethrough, a stiffening sleeve seated in said bore and having a flaring end and a nut in engagement with said sleeve for operating the same whereby the stop may be locked in position in the drain outlet.

6. In an overflow stop for lift and force 70 pumps, a resilient body adapted to be inserted in a drain outlet and having a suitable bore, a sleeve suitably carried by said body for stiffening the same and having a flaring end, threads on said sleeve and a nut in engagement with said sleeve producing relative 75 movement between the sleeve and resilient body whereby the flaring end is adapted to expand the body and lock the stop in the drain outlet.

7. In an overflow stop for lift and force 80 pumps, a resilient body adapted to be inserted in a drain outlet, a sleeve having a threaded portion carried by said body for stiffening the same and having a flaring end, 85 a nut in engagement with the threaded portion of said sleeve producing relative movement between the sleeve and resilient body whereby the flaring end is caused to raise or lower in said bore, whereby the body may be 90 expanded and the threaded end of said sleeve project a suitable distance beyond the top of the nut whereby the end is adapted for engagement with a suitable coupling or other device.

8. An overflow stop for lift and force 95 pumps, comprising a resilient body adapted to be inserted in a drain outlet, and jaws adapted to engage with the cross bars in the drain for assisting in holding the stop in 100 position.

EMIL NOPPEL.
